VALVE HEAD FOR BY-PASS PACKERS

Harry E. Lynn, Monterey Park, Calif., assignor to
 M. O. Johnston Oil Field Service Corporation,
 Los Angeles, Calif., a corporation of California

Application October 28, 1944, Serial No. 560,893

4 Claims. (Cl. 166—12)

1

This invention relates to oil well tools and particularly pertains to a valve head for bypass packers.

When packers are run into a well bore, particularly in instances where a casing has been set within the well, it has been found that the limited clearance between the circumference of the packer and the casing creates a relatively small area around the packer through which well fluid may bypass as it is displaced by the downwardly moving packer and other equipment attached thereto, such for example as an oil well testing tool. It has been found desirable, therefore, to create a central passageway through the packer of adequate area to allow the fluid to bypass and to thereby permit the well packer to be lowered rapidly into the well and through the fluids with which the well is filled. In these operations it is desirable to provide a bypass structure which is compact in construction and has sufficient strength to hold all of the parts in their assembled position, and to make it possible to readily replace these parts in the event of accidental breakage or abrasion. It is the principal object of the present invention, therefore, to provide a bypass packer head which is decidedly simple in construction, has great strength, and may be readily installed and replaced.

The present invention contemplates the provision of a packer mandrel upon which a tappet valve structure is fixed, and which mandrel is fitted with a sub and a lock member tending to hold the mandrel and the valve element securely together and permitting these elements to be easily assembled and dismantled when desired.

The invention is illustrated by way of example in the accompanying drawings in which:

Figure 1 is an enlarged view in longitudinal section and elevation showing a fragmentary portion of a bypass packer and the mandrel and valve structure embodying the present invention.

Fig. 2 is a view in transverse section through the mandrel and valve structure as seen on the line 2—2 of Fig. 1.

Referring more particularly to the drawings, 10 indicates the upper end of a bypass packer, said packer including an expandible packing element 11, a sleeve 12 upon which it is mounted, and a tapered valve seat 13 at the top of said sleeve. A web 14 extends transversely of the sleeve 12 and is formed integral therewith, said web having fluid circulating ports 15 therethrough. The web 14 has a central opening 16 therethrough to receive a tubular packer mandrel 17 which is associated with conventional types

2

of bypass packer structures and may be temporarily locked against movement relative to the sleeve 12. The locking mechanism is not a part of the present invention. The tubular mandrel 17 is here shown as having a central longitudinal flow passageway 18 through it and is shown as having an upper length of reduced diameter forming an outer cylindrical wall surface 19. The main body of the mandrel 17 has a wall surface 10 of larger diameter, as indicated at 20, and a tapered wall surface 21 occurs between these two lengths of mandrel. The surface 21 tapers upwardly and inwardly and forms a frusto-conical section which represents a relatively small degree of taper. This provides a limiting face on the mandrel. The reduced length of the mandrel 17 defined by the wall 19 extends through a bore 22 formed centrally of a valve head 23. The valve head 23 is cylindrical and of a wall thickness sufficient that it accommodates a tapered valve face 24 at the lower end thereof. The upper end of the valve head 23 has a reduced cylindrical portion 25 which is externally threaded, as indicated at 26, and engages the threaded bore 27 in the lower end of a sub 28. Within the sub 28 and forming a continuation of the threaded bore 27 is a smooth bore section 29 which communicates with a reduced bore 30 in said sub. The bore 30 15 communicates with a threaded tapered bore 31 formed within the upper box section of the sub 28. A pin 32 of a drill string section 33 is screwed into the bore 31 and forms a supporting connection for the packer with relation to the string of pipe upon which it is lowered into the well. 20 The mandrel 17 and valve head 23 are held in their assembled relation by a nut 34 which has a central threaded bore 35 through which the upper threaded portion 36 of the mandrel 17 extends. The lower end face of the nut 34 forms a downwardly tapered frusto-conical face 37 which seats upon a tapered seat 38 formed at the upper end of the valve head 23 and within the end of the bore 22. It will be seen that when 25 the frusto-conical face 37 engages the seat 38 and the nut 34 is tightened it will draw the tapered face 21 of the mandrel into the tapered end bore 22 of the valve head so that the valve head 23 will be firmly held against longitudinal movement upon the mandrel. The valve head 23 is held against rotational movement on the mandrel by keys 39, which are positioned within keyways 40 formed longitudinally of the bore 22 of the valve head 23 and keyways 41 formed longitudinally of the outer surface of the mandrel 17.

Attention should be called to the fact that in normal practice a sub similar to the upper portion of the sub 28 is used, and that a tubular mandrel comparable to the mandrel 17 is directly threaded into the lower end of this sub, the result being that the portion of mandrel occurring between the upper end of the packer 10 and the lower end of the sub is decidedly weak and may be damaged due to longitudinal and torsional strains imposed upon it. Furthermore, it will be seen that the connection between the upper end of such a threaded mandrel and the lower end of a sub as employed in usual practice is represented by a threaded section of relatively small diameter so that there is a danger that the threads will be injured or that the tubular mandrel might become loose. With the present structure the connection between the sub and the packer is represented by the threads 26 and 27 occurring on the sub and valve head respectively. This threaded section is of large diameter and the walls carrying the threads are both of considerable thickness to provide the necessary strength. At the same time it will be noted that the nut 34 which directly engages the upper end of the tubular mandrel merely acts to hold the various members in assembled relation and is not subjected to the lateral strain or torsion such as is adequately resisted by the assembled valve head 23 and sub 28.

In operation of the present invention the valve head 23 is mounted upon the upper extending portion of the mandrel 17 with its keys 39 in position. In Fig. 2 of the drawing three keys are shown as being used. This equalizes the strain although it will be understood that any number might be used. After the valve head 23 has been forced down so that its tapered bore 22' rests upon the tapered face 21 of the mandrel the nut 34 is tightened. This tends to pull the tapered portion 21 tightly into the seat 22' and also to force the frusto-conical face portion 37 of the nut down onto the seat 38. This provides a double seal between the mandrel 17 and the valve head 23 and with the aid of the keys 39 provides a rigid substantial connection between the valve head and mandrel structure. The lower box section of the sub 28 is then screwed onto the portion 25 of the valve head and tightened down against the shoulder 42 on the valve head. The structure is then in its assembled position and may be attached to the pin 32 of the supporting string when desired.

It will thus be seen that by the structure here disclosed a valve head assembly for bypass packers and the like is provided which has great strength, may be easily assembled and dismantled, and will provide a connection between a supporting string of pipe and a packer which is not liable to break or become distorted.

While I have shown the preferred form of my invention as now known to me, it will be understood that various changes may be made in combination, construction and arrangement of parts by those skilled in the art, without departing from the spirit of my invention as claimed.

Having thus described my invention, what I claim and desire to secure by Letters Patent is:

1. A valve for bypass packers or the like, comprising a tubular valve head, a mandrel extending through said head, means on the mandrel

engaging one end of the head limiting movement of the head with respect to the mandrel in one direction, a nut on the mandrel engaging the opposite end of said head limiting movement of the head with respect to the mandrel in the opposite direction, and a sub secured to said head independently of said mandrel for securing said valve to a drill string.

2. A valve for bypass packers or the like, comprising a valve head having a central bore therethrough, a tubular mandrel extending through said head, cooperating tapers on said mandrel and one end of said head limiting downward movement of said head with respect to said mandrel, a nut on the mandrel engaging the opposite end of said head to limit upward movement of said head with respect to said mandrel and to secure the mandrel and head in fixed relation, a sub threadedly engaging said head externally of said nut and independently of said mandrel, said sub including means for securing said valve to a drill string.

3. A structure as set forth in claim 2 including means for holding the valve head and mandrel against relative rotation.

4. A valve for bypass packers and the like, which packers are formed with a seat providing a bypass opening through the packer; comprising a tubular mandrel extending centrally of the packer through which mandrel fluid may flow, said mandrel having a lower length of larger outer diameter and an upper length of lesser outer diameter, a relatively long tapered shoulder occurring between said two lengths of said mandrel, a threaded portion at the upper end of the mandrel length of lesser diameter, a valve head formed with a central bore through which said upper length of mandrel extends and with which it fits, said valve head at its lower end being formed with a tapered valve face adapted to rest upon a complementary tapered valve seat of the packer and an upper threaded end of a lesser diameter than the outer diameter of the valve head, a tapered counterbore formed at the lower end of the valve head to rest against the tapered shoulder of the mandrel, a tapered counterbore at the upper end of the valve head to provide a sealing seat, a threaded nut mounted upon the upper threaded end of the mandrel, a tapered sealing seat at the lower end of the nut adapted to rest against the sealing seat of the valve head, keys between the mandrel and the valve head preventing relative rotation of said members, a tubular sub having a downwardly presented threaded box receiving the upper threaded end of the valve head and accommodating the nut on the mandrel, and a threaded connection at the upper end of said sub for receiving a complementary end of pipe section.
